UNITED STATES PATENT OFFICE.

LEWIS T. DIEBOLT, OF LOGANSPORT, INDIANA.

LOCK.

1,350,213.

Specification of Letters Patent. Patented Aug. 17, 1920.

Application filed July 22, 1919. Serial No. 312,531.

To all whom it may concern:

Be it known that I, LEWIS T. DIEBOLT, a citizen of the United States, residing at Logansport, in the county of Cass and 5 State of Indiana, have invented new and useful Improvements in Locks, of which the following is a specification.

This invention relates to locks and has particular reference to means employed for 10 locking the steering post of a motor vehicle, against movement, with a view of preventing access of the machine, for its use by unauthorized persons.

To this end, the invention makes use of a 15 casing having a cover, which may be locked in any suitable manner, the steering post projecting through the casing and coöperating with manually operable means arranged within the casing, for holding the 20 steering post against movement, which obviously prevents the machine from being properly steered or guided should the same be moved.

It is also the object of this invention, to 25 arrange the ignition switch or operating element within the casing, so they cannot be tampered with during the absence of the owner from the machine.

In carrying out the invention, the cover 30 is designed to provide a compartment for the reception of the elements of a combination lock, which holds the cover in its closed position, thus preventing access being had to the casing by anyone other than those 35 having knowledge of the combination.

Other objects and advantages will appear 40 when the following detail description is read in connection with the accompanying drawings, the invention residing in the construction, combination and arrangement of parts as claimed.

In the drawings forming part of the specification, like numerals of reference indicate similar parts in the several views and 45 wherein:

Figure 1 is a fragmentary perspective view of a machine showing the invention associated therewith.

Fig. 2 is a vertical sectional view taken 50 through the instrument board of the machine and the casing in which the locking mechanism is arranged.

Fig. 3 is a horizontal sectional view taken through the same parts.

Fig. 4 is a detail vertical sectional view 55 taken transversely through the steering post.

Fig. 5 is an enlarged detail view showing the position of parts when the steering post is locked against movement. 60

Fig. 6 is a horizontal section taken through the cover.

Fig. 7 is a vertical transverse sectional view therethrough.

In carrying out the present invention, use 65 is made of a casing 10 which may be constructed from any suitable material, and includes front and rear walls 11 and 12 respectively, top and bottom walls 13 and 14 respectively and end walls 15. The front 70 wall 11 is provided with an opening to permit access to the interior of the casing, this opening being normally closed by a cover 16 which is preferably hinged upon the front wall as at 17. The casing 10 is arranged 75 within the hood 18 of the machine and secured in any suitable manner upon the adjacent side of the instrument board 19. This board is provided with an enlarged opening, of a size and configuration to accommodate the cover 16, the latter being arranged to lie flush with the opposite side of the board as shown in Fig. 1.

Arranged within the casing 10 is an arm 20, the latter being vertically disposed, and 85 suitably secured to the front wall 11. This arm however is obliquely disposed with respect to the said front walls so as to be spaced therefrom. The free extremity of the arm is bifurcated as at 21 for a purpose 90 to be presently described, while the separated portions 22 defined by said bifurcation are provided with alined apertures or openings 23. Fixed to the rear wall 12 is a bearing 24 including a hollow boss 25 which 95 slidably receives the adjacent end of a locking bolt 26 the opposite end 27 thereof being arranged to slide through the openings 23 of the arm 20. The steering post 28 passes through the casing operating in suitable bearings in the front and rear walls 11 and 12 respectively, the post 28 being arranged in close proximity to the arm 20. A disk 29 is fixed upon the post 28 for rotation therewith, the disk being arranged to 105 operate between the separated portions 22 of the arm 20. To permit of the proper manipulation of the steering mechanism,

the bolt 26 is normally disposed with its end 27 out of the path of movement of the disk 29, but when it is desired to lock the steering post against movement, to prevent use of the machine during the absence of the user, the bolt 26 is actuated to pass through the slot 30 of the disk and also through the openings 23 of the separator 22 of the arm. It is of course manifest, that 5 the steering post must be rotated to bring the slot 30 of the disk in alinement with the openings 23, to permit of free passage of the bolt 26 through said parts for the purpose just mentioned. It is to be understood 10 however, that the slot 30 may be arranged or disposed with relation to the posts 28, so that when the slot 30 is brought into registration with the openings 23, the front wheels of the vehicle may be either in 15 20 straight away position, or arranged at an angle with respect to the curve or the side of the post.

Any suitable means may be employed for actuating the bolt 26, but as shown in this 25 specific instance, use is made of a shaft 31 journaled in apertured lugs 32, projecting from a base plate 33 which is secured to the bottom 14 of the casing. Fixed to one end of the shaft is a manually operable lever 30 34 disposed in parallelism with the finger 35 secured to the opposite end of the shaft for rotation therewith. The intermediate portion of the bolt is squared as at 36 and provided with a slot 37 for the reception of 35 the adjacent extremity of the finger 35. Manifestly, the lever 34 is moved in the direction of the front wall 11, the finger 35 is actuated to adjust the locking bolt to its active position. The squared intermediate 40 portion 36 of the bolt, provides the latter with shoulders 38 which limits the movement of the bolt both toward and away from the arm 20. A member 39 projects forwardly from the rear wall 12 and is provided at an appropriate point in its length 45 with a lug 40 by beveling or cutting away the member 39 as at 41. The lever 34 contacts with the lug 40 in holding the bolt 26 immovable in either active or inactive position. In other words, the lever 34 engages 50 the lug at one side when the bolt 26 is in normal position, and subsequent to the adjustment of the bolt, to active position, the lever 34 is arranged to engage the opposite side of the lug thereby holding the parts including the steering post 28 in fixed position.

Arranged within the casing 10 and secured to the rear wall 12 in the bottom 14 55 thereof is a strip 42 which supports the switch operating element 43 which controls the lamp circuit, and the ignition system of the machine. By reason of this arrangement, it is obvious that the switch elements 60 are concealed from view and locked within

the casing so that they cannot be tampered with by unauthorized persons, during the absence of the owner from the machine.

The cover 16 for the casing is designed to provide a compartment 44 for the reception 70 of a lock mechanism by which the cover is secured in closed position. While any suitable means may be employed for this purpose, I preferably make use of a main locking bolt 45 which operates through an opening 75 in one end of the cover, and simultaneously movable auxiliary bolts 46 and 47 respectively, which operate to openings in the opposite sides of the cover. All of the 80 said bolts are provided with rack teeth 49 which mesh with the teeth of a cog 50, so that by rotating the latter in reverse direction, the bolts 45, 46 and 47 will be thrown into and out of engagement with the front 85 wall 11 of the casing. The cog wheel 50 is fixed upon a shaft 51 journaled within the compartment for rotation and projecting beyond the cover to accommodate a handle 52. The bolts 45, 46 and 47 form part of a combination lock mechanism, which also includes a plurality of super-imposed gear 90 wheels 53 of varying diameters, and all mounted for rotation upon the shaft. These gears are arranged in pairs, each pair including a large gear and a relatively small 95 gear fixed relatively. The large gears are provided with relatively short notches 54 and a relatively deep notch 55. A pinion 56 is provided for each of the small gears, and each pinion is carried by one of the 100 shafts 57 journaled within the compartment 44 for rotation. The shafts 57 are provided with knobs 58 arranged exteriorly of the cover for rotating said shaft, with a view of bringing the relatively deeper notches 55 of 105 said gears into registration with each other, and in alinement with the main locking bolt 44. The disposition of parts is such that this is necessary before the locking bolts 45, 46 and 47 can be actuated, as the 110 main locking bolt 45 must be within the deep notches 55 of the gears when retracted. Consequently, the cover 16 cannot be opened by anyone except those familiar with the combination, and as is the case with any 115 combination lock, the combination can be changed from time to time.

In addition to the combination mechanism, the cover is also provided with a key actuated bolt 59, which is adapted to be 120 projected into a notch or recess 60, in one of the auxiliary bolts 46, thus requiring the use of a particular type of key to release the locking bolts for adjustment. Thus should unauthorized persons, by chance succeed in manipulating the combination mechanism to effect a release of the main locking bolt 45, this together with the auxiliary bolts 46, and 47 all of which move in 125 unison, would be held against movement 130

by means of the key actuated bolt 59. The invention will not only serve to prevent the access of machines, but is designed to permit of its application to any type or 5 make of car without any alterations or modifications.

While I have shown and described what I consider the preferred embodiment of the invention, I desire to have it understood 10 that this is merely illustrative, that I do not limit myself to the exact construction and arrangement of parts disclosed, and that such changes may be resorted to when desired as fall within the scope of what is 15 claimed.

Having thus described my invention what I claim is:

1. Means for locking the steering post of a vehicle against rotation, comprising a 20 casing through which the steering post extends, an arm secured within the casing and having a bifurcated extremity, a member carried by the post for rotation therewith, and movable between the separated portions 25 of the arm defined by said bifurcations, a locking bolt, said member carried by the post being designed to receive said bolt, said separated portions having alined openings for the reception of said bolt, said bolt 30 being normally arranged to permit rotation of the post and said member, and means for actuating said bolt.

2. Means for locking the steering post of a vehicle, against rotation, comprising a 35 casing through which the steering post extends, a bolt arranged within the casing, means for supporting said bolt for sliding movement, a member projecting from one wall of the casing, a lug formed on said member at a point in its length, a manually 40 operable lever associated with the bolt for actuating the latter, said lever being arranged to alternately engage the opposite sides of said lug, whereby said lever is maintained in adjusted position, an element 45 carried by said post for rotation therewith, and designed to receive said bolt.

3. Means for locking a steering post of a vehicle against rotation, comprising a support to which the steering post extends, a 50 bolt mounted for sliding movement, means for supporting the bolt, a member carried by said post and designed to receive the bolt, said bolt being normally separated from said member, a shaft journaled for 55 rotation, a member projecting from the shaft and associated with the bolt for sliding the latter, toward and away from said member, a lever for rotating the shaft, means for holding the lever in a given position.

In testimony whereof I affix my signature.

LEWIS T. DIEBOLT.
